UNITED STATES PATENT OFFICE

REUBEN E. OTTENHEIMER, OF BALTIMORE, MARYLAND

DESIGN FOR A REFRIGERATOR

Application filed May 7, 1930. Serial No. 35,529. Term of patent 7 years.

To all whom it may concern:

Be it known that I, REUBEN E. OTTENHEIMER, a citizen of the United States, residing at Baltimore, Maryland, have invented a new, original, and ornamental Design for Refrigerators, of which the following is a specification, reference being had to the accompanying drawings, forming a part thereof.

In the drawings:—

Fig. 1 is a front view in perspective; and
Fig. 2 is a rear view in perspective of the article showing my new design.

I claim:

The ornamental design for a refrigerator, as shown.

REUBEN E. OTTENHEIMER.
